UNITED STATES PATENT OFFICE.

WILLIS J. TUTTLE, OF ALBANY, WYOMING.

HOSE-CLAMP.

1,052,103.

Specification of Letters Patent.

Patented Feb. 4, 1913.

Application filed July 27, 1911. Serial No. 640,820.

To all whom it may concern:

Be it known that I, WILLIS J. TUTTLE, a citizen of the United States, residing at Albany, in the county of Albany, State of Wyoming, have invented certain new and useful Improvements in Hose-Clamps; and I do hereby declare the following to be a full, clear, and exact description of the invention, such as will enable others skilled in the art to which it appertains to make and use the same.

This invention relates to new and useful improvements in hose clamps.

An object of this invention is the provision of a hose clamp comprising a pair of hinged arcuate sections provided at their free ends with interlocking means whereby the same may be brought together and held against displacement.

20 A further object of this invention is to improve and simplify devices of this character rendering them comparatively simple and inexpensive to manufacture, reliable and efficient in use and readily operated.

25 With the above and other objects in view this invention resides in the novel features of construction, formations, combinations and arrangements of parts to be hereinafter more fully described, claimed and illustrated in the accompanying drawing, in which:—

30 Figure 1 is a side elevation of a portion of a nozzle and section of hose secured thereto by my improved clamp. Fig. 2 is a plan view thereof. Fig. 3 is a transverse sectional view taken on the line 3—3 of Fig. 1. Fig. 4 is a longitudinal sectional view taken on the line 4—4 of Fig. 2.

35 Referring to the drawing by similar characters of reference throughout the several views, the numeral 5 designates a portion of a nozzle, the terminal of which is surrounded by a section 6 of hose. My improved clamp 7 surrounds the said hose 6 and holds it against displacement with respect to the nozzle. This clamp 7 comprises a pair of arcuate sections 8 and 9, one of which has extending therefrom a tongue 10 formed upon its outer terminal 40 with a cross pin 11.

45 The section 9 is slotted at one end and bent to form a pair of spaced eyes 12 which engage the pin 11 upon the opposite sides of the tongue 10. The free ends of these

50 arcuate sections 8 and 9 have formed thereon ears 13 and 14, respectively, which extend substantially radially from the ring 15 described by the arcuate sections 8 and 9. These ears 13 and 14 are apertured as at 16 for the reception of a threaded clamping 55 bolt 18 provided upon one end with a head 19 and having adjustable upon the opposite end a locking nut 20 which is adapted to be held against rotation by the engagement between one of its sides and the adjacent 60 end of one of the arcuate sections.

65 The section 8 is enlarged at its juncture with the ear 13 and is extended therebeyond to produce a pair of spaced guides 21 which engage the opposite sides of the arcuate 70 member 9. The ear 14 is extended upon the opposite sides of the end of the member 9 and is provided with depending terminals 22 which produce grooves 23 for the engagement with the guides 21. If desired 75 the outer face of the ear 14 may be countersunk as at 24 for the reception of the head 19 of the bolt.

80 From the foregoing disclosures taken in connection with the accompanying drawing, it will be manifest that a hose clamp is provided for which will fulfil all of the necessary requirements of such a device.

85 Having thus fully described this invention, what I claim as new and desire to obtain by Letters Patent, is:

90 The combination in a hose clamp, of a pair of arcuate sections hinged at their ends upon one side thereof, radially extending ears projecting from the free ends of the sections, guides extending from one of the sections beyond the adjacent ear and engaging the opposite sides of the other section, extensions formed upon one of said ears, 95 depending terminals provided upon the extensions producing recesses for engagement with the guides, a clamping bolt extending through the ears and a nut threaded thereon and held against rotation by its engagement with one of said sections, substantially 100 as and for the purposes set forth.

105 In testimony whereof, I affix my signature, in presence of two witnesses.

WILLIS J. TUTTLE.

Witnesses:

E. A. WILKINSON,
ALICE HUNT.
